CONTROL KNOB

Richard G. Munroe, Lexington, Mass., assignor
to Raytheon Manufacturing Company, Newton,
Mass., a corporation of Delaware

Application November 13, 1951, Serial No. 17,373

Term of patent 14 years

(Cl. D26—13)

To all whom it may concern:

Be it known that I, Richard G. Munroe, a citizen of the United States, residing at Lexington, in the county of Middlesex and Commonwealth of Massachusetts, have invented a new, original, and ornamental Design for a Control Knob, of which the following is a specification, reference being had to the accompanying drawing, forming part hereof, in which:

Fig. 1 is a top plan view of a control knob, showing my new design;

Fig. 2 is a front elevation view;

Fig. 3 is a left side elevation view;

Fig. 4 is a right side elevation view of a control knob; and

Fig. 5 is an enlarged fragmentary detail view of the knurl.

I claim:

The ornamental design for a control knob, substantially as shown.

RICHARD G. MUNROE.
